UNITED STATES PATENT OFFICE.

CARL SCHRAYSSHUEN, OF PROVIDENCE, RHODE ISLAND, ASSIGNOR TO SPEIDEL CHAIN CO., A FIRM COMPOSED OF FREDERICK SPEIDEL AND EUGEN SPEIDEL, BOTH OF PFORZHEIM, GERMANY, DOING BUSINESS AT PROVIDENCE, RHODE ISLAND.

BAND BRACELET.

Application filed January 3, 1927. Serial No. 158,552.

- This invention relates to an improved construction of band type of bracelet; and has for its object to provide such a bracelet formed of a master ring having a plurality of ornaments fixed in spaced relation about its periphery and having a plurality of separate rings connected to said ornaments to lie side by side with the master ring to form when assembled a band bracelet.
- With these and other objects in view, the invention consists of certain novel features of construction, as will be more fully described, and particularly pointed out in the appended claims.
- In the accompanying drawings:
- Figure 1 is a side elevation of my improved band bracelet.
- Figure 2 is an edge view of the band bracelet with one of the ornaments partly in section.
- Figure 3 is a side elevation of one of the rings detached.
- Figure 4 is an edge view showing a plurality of ornaments as connected to the master ring with the other rings of the bracelet removed.
- Figure 5 shows the ornaments as connected to the master ring and a plurality of other rings positioned on either side thereof to cooperate with the master ring, also showing the edge rings in position to be snapped into place to engage and be held by the ornamental members.
- It is found of advantage in the construction of an ornamental bracelet resembling somewhat the so-called "slave bracelet" type having large ornaments or settings for gems or other ornaments arranged about the bracelet and to secure these ornaments in spaced relation about a master ring and also to provide a plurality of separate rings which may be of a variety of colors, such as yellow gold, white gold and green gold, which may be snapped or otherwise positioned in engagement with these ornaments on the master ring to cooperate with the master ring to form a band member of a variety of different colors; also to connect ornaments of a variety of designs to this master ring to provide a variety of designs either as gem settings or other ornaments; and the following is a detailed description of the present embodiment of my invention

and showing one arrangement of rings and ornaments by which these advantageous results may be accomplished:—

With reference to the drawings, 10 designates the master ring which in this particular case is made of round wire into a continuous band form and to the periphery of this band I have attached a plurality of ornaments 11.

These ornaments are herein shown as being of the box type of gem settings in which large gems 12 of various shapes and colors are seated each on its shoulder 13 and retained in the setting by the bending of the lip 14 over the edge of the gem. In this construction, it will be seen that the central under portion 15 of the setting is hollow and the peripheral edges 16 of the setting rests upon the periphery of the master ring where these edges are firmly secured by solder or otherwise, thereby permitting an arcuately curved portion of the periphery of this ring to extend up into the recess of the hollow portion of the setting.

By this construction, it will be seen that the separate or independent rings 17 in order to be positioned along side of the master ring 10 must be snapped beneath the side edges 18 of the gem setting, which side edges due to the engaged curved portion of the ring serves to prevent these rings from being inadvertently removed from engagement with the settings and as many of these separate rings may be snapped into these gems on each side of the master ring as is necessary to fill the space between the master ring and the edges 18 of the setting, thus providing a broad band made up of a multiplicity of these rings which may be assembled all in a single color or the band may be made up of rings of a variety of colors to suit the tastes of the different wearers and these different detachable rings may be made interchangeable with different band bracelets so that they may be removed and the different wearers may exchange them one for another, if desired to perform the function somewhat of a "friendship" bracelet.

My improved construction of bracelet is very inexpensive to manufacture as the labor of assembling the parts is reduced to the minimum and by the use of rings of differ-

ent colors may be made up with a variety of different artistic effects and when completed is very handsome and attractive in appearance.

5 The foregoing description is directed solely towards the construction illustrated, but I desire it to be understood that I reserve the privilege of resorting to all the mechanical changes to which the device is susceptible, 10 the invention being defined and limited only by the terms of the appended claims.

I claim:

1. A band bracelet comprising a master ring, a plurality of ornaments fixed in 15 spaced relation about said ring, means in said ornaments for receiving other rings, and a plurality of separate rings of corresponding size received in said receiving means to lie side by side with said master ring to form 20 when assembled a band bracelet.

2. A band bracelet comprising a master ring, a plurality of ornaments fixed to said ring in spaced relation about its periphery, means in said ornaments for receiving other 25 rings and a plurality of separate rings arranged to snap into engagement with said receiving means to form when assembled a band bracelet.

3. A band bracelet comprising a master 30 ring, a plurality of ornaments fixed to said

ring in spaced relation about its circumference, the inner surface of said ornaments being recessed, and a plurality of separate flexible rings arranged to have portions of their peripheries snap into the recesses in 35 said ornaments to form when assembled with the master ring a band bracelet.

4. A band bracelet comprising a master ring, a plurality of ornaments fixed to said ring in spaced relation about its circumference, said ornaments being recessed in their inner surface, and a plurality of separate flexible rings snapped into engagement with 40 said ornaments so that portions of their peripheries will extend into the recessed portion thereof, and the marginal edges of the ornaments about its recess serving to 45 removably retain the rings therein to form when assembled a band bracelet.

5. A band bracelet comprising a master ring, a plurality of ornaments fixed to said ring in spaced relation about its periphery, said ornaments extending on either side of 50 said ring, and a plurality of separate rings releasably connected to said ornaments on either side of the master ring to jointly form 55 a band of extended width.

In testimony whereof I affix my signature.

CARL SCHRAYSSHUEN.
